CLAIM

The ornamental design for a storage rack for sterile packaging, as shown and described.

DESCRIPTION

FIG. 1 is a top, front and right perspective view of a storage rack for sterile packaging showing our new design.

FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevational view thereof; and,

FIG. 7 is a rear elevational view thereof.

The broken lines in the drawings depict portions of the storage rack for sterile packaging that form no part of the claimed design.

The dot-dash-dot broken lines in the drawings depict the boundaries of the claim and form no part thereof.
